UNITED STATES PATENT OFFICE.

HENRY JAMES BRASHIER, OF LONDON, ENGLAND.

RECEPTACLE FOR BLACKING, TOOTH-PASTE, AND LIKE PLASTIC MATERIALS.

1,296,473.

Specification of Letters Patent.

Patented Mar. 4, 1919.

Application filed March 27, 1918. Serial No. 225,075.

To all whom it may concern:

Be it known that I, HENRY JAMES BRASHIER, a subject of the King of Great Britain, residing at London, England, have 5 invented certain new and useful Improvements in Receptacles for Blacking, Tooth-Paste, and like plastic Materials, of which the following is a specification.

This invention relates to improvements in 10 that class of receptacle for plastic materials such as blacking, toothpaste, ointment or the like which has a container, (hereinafter also called a "lid") provided with a piston for ejecting the plastic material through an orifice in the upper part of the container. This 15 class of receptacle is objectionable and has hitherto had little or no commercial value, owing to the leakage of material between the piston and container, no means having 20 been provided to trap any material which has so escaped through such leakage. Any leakage of this kind also is detrimental to plastic materials such as blacking, ointment or the like owing to the rapidity with which 25 oily or other plastic ingredients vaporize, resulting in drying and hardening of the compounds before they can be used.

The difficulty is overcome according to 30 the invention which consists in a receptacle of the kind referred to comprising a box having a central piston portion in spaced relation to the side of the box, forming therewith an annular pocket, and a slotted lid the side of which engages within and 35 fits the side of the box and enters the aforesaid pocket. Any material leaking between the lid and piston is retained within this pocket. An auxiliary lid fitting over the slotted lid further seals and protects the 40 contents.

In one form a packing disk of cardboard or like material is inserted within the slotted lid so that such disk rests on and is operated (on pressure being used) by the piston, and 45 suitable means are provided to hold the disk in the lid even when uneven pressure is applied to the lid tending to tilt the disk.

In the drawings:—

Figure 1 is a perspective view of one form 50 of a container or receptacle according to the invention.

Fig. 2 being a perspective view of an auxiliary lid therefor.

Fig. 3 is a sectional elevation of the same 55 container and the auxiliary lid in position thereon.

Fig. 4 is a plan of the container with the auxiliary lid removed.

Fig. 5 is a sectional elevation of a slightly modified form of container.

Fig. 6 is a sectional elevation of a further form in which a packing disk is used.

Fig. 7 being an inverted plan of the lid with the disk in position showing the lugs for holding the disk.

Fig. 8 is a sectional elevation of a still further form.

In all the figures similar reference numerals indicate corresponding parts.

In the form of the invention illustrated 70 by Figs. 1 to 4, a cylindrical box has a vertical side 1. Inside the box an inverted cup 2 forms an internal upstanding piston portion in spaced relation to the side 1 of the box so as to form therewith an annular 75 pocket 3. The side 1 projects above the top 4 of the piston portion 2. A lid provided with a central slot 6 for the ejection of the contents of the box has a side 7 engaging within and fitting the side 1 of the box. It 80 also fits the side of the piston portion 2. The lid 5 has a circular rim or beading 8 surrounding the slot 6, thereby forming a convenient finger basin for the ejected portion of the contents of the lid or container. 85 When the contents are to be ejected the operator can either take the box in his hands or rest it upon some surface such as a table and press the lid farther into the box and the piston will then force the contents through 90 the slot. Practically the whole of the contents may be thus ejected so that there is a minimum of waste. An auxiliary lid 9 fits over the lid 5 and prevents evaporation 95 of oily or other matter in the contents through the slot 6.

In the form shown in Fig. 5 the lid 5 is provided with a depression or basin 10 in which the slot 6 is formed. A corresponding depression 21 is formed in the top 4 of 100 the piston portion 2.

In the forms shown in Figs. 6, 7 and 8, the lid 5 is fitted with a packing disk 11 of cardboard or like material, the lid 5 having lugs 12 for holding the disk in position and 105 preventing it from tilting should an uneven pressure be applied to the lid, 5. The piston portion 2 is shown in Fig. 6 pressed up from the same piece of material as the side 1 of the box. To allow for the descent of the 110 lugs 12 when the contents are being ejected (see Fig. 8) the annular pocket 3 is of suit-

able width. In Fig. 8 the piston 2 is shown as a separate cup merely loosely inserted or soldered or otherwise secured to the bottom 13 of the box. The piston or cup 2 has a 5 flange 15 which fits against the side 1 of the box and centralizes the cup or piston.

In order still further to prevent evaporation of the contents before use a thin sheet of metal foil 14, Fig. 6, is laid against the 10 inside of the top of the lid 5. The portion of the foil beneath the slot 6 is pierced or scraped away by a knife when the contents are to be used. With a box or receptacle according to the invention plastic materials 15 containing oily or other matters can be packed and retained in a plastic state for long periods. Moreover the contents can be used without soiling or mess and without any appreciable waste.

20 I claim:—

1. A receptacle for plastic material comprising a box having a central piston portion in spaced relation to the side of the box forming therewith an annular pocket, and 25 an apertured lid for containing the plastic material placed over such central piston portion the side of which lid engages within and fits the side of the box and during the whole period of use in the extrusion of the 30 contents thereof enters the aforesaid pocket.

2. A receptacle for plastic material comprising a box having a central piston portion in spaced relation to the side of the box forming therewith an annular pocket and an ap- 35 pertured lid for containing the plastic material placed over such central piston portion the side of which lid engages within and fits the side of the box and during the whole period of use in the extrusion of the 40 contents thereof enters the aforesaid pocket and an auxiliary lid adapted to fit over the afore- said slotted lid, substantially as and for the purpose hereinbefore set forth.

45 3. A receptacle for plastic material comprising a box having a central piston portion

in spaced relation to the side of the box forming therewith an annular pocket, and an apertured lid for containing the plastic material placed over such central piston portion the side of which lid engages within and fits the side of the box and during the whole period of use in the extrusion of the contents thereof enters the aforesaid pocket, and a cardboard disk above said piston portion and fitting inside said lid, substantially as 50 and for the purpose hereinbefore set forth.

4. A receptacle for plastic material comprising a box having a central piston portion in spaced relation to the side of the box forming therewith an annular pocket, 60 and an apertured lid placed over such central piston portion the side of which lid engages within and fits the side of the box and enters the aforesaid pocket, and a cardboard disk above said piston portion and fitting inside 65 said lid which is provided with lugs to hold said disk, substantially as and for the purpose hereinbefore set forth.

5. A receptacle for plastic material comprising a box having a central piston portion in spaced relation to the side of the box forming therewith an annular pocket, and an apertured lid placed over such central piston portion the side of which lid engages 70 within and fits the side of the box and enters the aforesaid pocket, and a cardboard disk above said piston portion and fitting inside 75 said lid which is provided with lugs to hold said disk, and an auxiliary lid adapted to fit over the aforesaid slotted lid, substantially as and for the purpose hereinbefore set forth.

In testimony whereof I have signed my name to this specification in the presence of two subscribing witnesses.

HENRY JAMES BRASHIER.
